WITNESS:

F. E. Fisher
INVENTOR
BY *Victor J. Evans*

ATTORNEY

UNITED STATES PATENT OFFICE

FRANK E. FISHER, OF GLEN ARBOR, MICHIGAN

SPARK ARRESTER

Application filed April 26, 1926. Serial No. 104,794.

This invention relates to spark arresters for use upon and in conjunction with chimneys contemplating a housing member positioned upon the top of the chimney and having a shelf positioned at an appropriate height thereof and having its respective side walls spaced therefrom to permit smoke to pass outwardly from the chimney but deflect sparks downwardly within the chimney in order that the roofs of houses may not be set afire.

Another object resides in the provision of a cover arranged upon the upper portion of the housing member and having a relatively small cut-out portion provided therein immediately above the shelf to permit the exhaust of smoke from the housing member.

With the above and other objects in view, the invention further includes the following novel features and details of construction, to be hereinafter more fully described, illustrated in the accompanying drawing and pointed out in the appended claim.

In the drawing:—

25 Figure 1 is a fragmentary elevation of a chimney with the present invention applied and used in conjunction therewith;

Figure 2 is a vertical sectional view of the invention; and

30 Figure 3 is a transverse section illustrating the arrangement and support of the shelf with the housing member.

Referring to the drawing in detail, wherein like characters of reference denote corresponding parts, the reference character 10 indicates a chimney having a shelf or enlarged portion 11 formed upon the upper end thereof; all of which is of the usual and conventional form and in no way consists of any 35 subject matter pertaining to the invention.

The invention resides in the provision of a box like housing member 12 preferably formed of thicknesses of coarse and fine wire or other reticulated or foraminated material 40 and which supports within its enclosure, defined at an appropriate point in the height and transversely thereof, a correspondingly constructed shelf 13 falling short of the dimensions of the box like housing 12 and having hooks 14 secured within the corners 45

thereof which extend inwardly from the corner portions of the housing in the manner as illustrated in Figures 2 and 3 of the drawing.

A cover 15 being preferably constructed of coarse wire meshing, having its respective edges bent downwardly upon themselves and fitting over the opposite and outer sides of the box like housing 12 and including an elongated cut-out portion 16 therein is positioned immediately upon and in spaced relation to the shelf 13. Retractile springs 17 having hooks 18 provided upon their upper ends and fitted within the opposite and downwardly extending side edges of the cover 15, while their opposite ends are associated with angularly disposed substantially L-shaped attaching plates 19 lying flush with the outer surface of the shelf or enlarged portion 11 and the chimney 10, while the opposite portions thereof engage the under sides of such enlarged portion, whereby the device in its entirety may be positioned against accidental displacement and retrograde movement upon the chimney, directly above the flue thereof 75 in order that sparks emitted from the chimney will be deflected downwardly within the chimney flue, but yet permit the smoke to pass therethrough and around the side edges thereof and through the side walls of 80 the housing. The cover 15 serves as an auxiliary to the shelf 13 to catch and deflect such sparks as may pass between the side edges of the shelf and the inner side walls of the housing member 12 and upon the outer side 85 of the shelf 13.

The above entitled invention offering a device which may prove of great value to persons having faulty chimneys emitting volumes of sparks and which will materially reduce chimney fires.

The invention is susceptible of various changes in its form, proportions and minor details of construction, and the right is herein reserved to make such changes as properly fall within the scope of the appended claim.

Having thus described my invention what I claim is:

A spark arrester comprising a housing 100

member arranged above the discharge end of a chimney, a combined shelf and baffle plate horizontally disposed within the housing member in spaced relation to the ends and side walls thereof and supported at its corners from the intersections thereof, a cover carried upon the member having downwardly deflected marginal edges extended over the upper edges of the end and side walls of the housing member, and said cover being provided with a centrally arranged elongated slot located immediately above the combined shelf and baffle plate and falling short of extending terminally thereof the length of the said shelf.

In testimony whereof I affix my signature.
FRANK E. FISHER.
